1720.

William W. Skaats' Design for Lamp Chimney.
Assigned to Gideon Skaats.
Patented July 17, 1863.

Des 1720

William H. Shaatz, of Brooklyn, N. Y.

Wssor to

Edwin Shaatz of Brooklyn, N. Y.

Letter Patent No 1720. Dated, Feb 17 1863,

The schedule referred to in these Letters Patent and making part of the same.
To all whom it may concern:

Be it known that I, William H. Shaatz, of Brooklyn, in the County of Kings, and State of New York, have invented or produced a new and original design for a Glass Lamp Chimney; and I do hereby declare that the following is a full, clear and exact description of the same, reference being had to the accompanying drawings making a part of this specification, in which,

Figure 1, is an elevation of a Glass Lamp Chimney showing my design.

Figure 2, a vertical central section of the same, taken in the line x. x. Figure 1.

Similar letters of reference indicate corresponding parts in the two Figures.

The chimney A, is formed in its longitudinal

profile with a gradual swelling curve which is composed of two portions of circles and a portion of an ellipse, and every horizontal or transverse section of the chimney, that is to say, a horizontal or transverse section taken in any part of it, is a circle.

The lower part of the chimney has its longitudinal profile form of a curve a, which is a portion of a circle taken from the point a' as a centre and the central portion is formed of a curve b, taken from the point b' as a centre. These centre points are shown at both sides of the chimney in Figure 2.

The upper part c of the chimney is formed of a portion of an ellipse. The three curves a, b, c, all unite so as to give a symmetrical bulge to the chimney the greatest diameter of which is in a plane which intersects the centre points b', and which is a trifle below the centre of the chimney, that is to say, the centre of its height. The parts c are of sufficient length or prolonged to such an extent as to render the orifice of the chimney a little smaller in diameter than the opening at its base, and a line drawn through the centre points a', b', will touch the upper end of the chimney.

Having thus described my invention, I claim as new and desire to secure by Letters Patent, as a Design for a Flap Lamp chimney.

The configuration composed as shown and described of the curves a, b, c, to form the longitudinal profile of a chimney, any horizontal or transverse section of which is a circle.
